UNITED STATES PATENT OFFICE.

EUGEN ESSICH, OF STUTTGART, GERMANY.

ELECTRIC LIGHTING DEVICE.

1,171,509.

Specification of Letters Patent.

Patented Feb. 15, 1916.

Application filed April 22, 1915. Serial No. 23,199.

To all whom it may concern:

Be it known that I, EUGEN ESSICH, of 77 Hohenheimerstrasse, Stuttgart, in the Kingdom of Wurttemberg, German Empire, civil 5 engineer, have invented certain new and useful Improvements in Electric-Lighting Devices, of which the following is a specification.

My invention relates to electric glow 10 lamps and its particular object is to reduce the radiation of heat in such lamps in order to increase their lighting capacity.

The electric energy supplied to a glow 15 lamp is transformed therein into heat and light; the smaller the quota of heat radiated into the surrounding atmosphere, the greater the lighting power of the lamp. The modern metal filament glow lamps having the bulb filled with an inert gas have a 20 comparatively short life; when the filament is consumed the whole lamp including the fittings is almost worthless. Moreover in these lamps a heat emission takes place 25 which is favored by the circulation of the gas filling the bulb. It may not be impossible to diminish the heat emission by providing such glow lamps with a double walled bulb, the space between the outer and inner walls of the bulb being exhausted. 30 Such a construction however is far more expensive than the ordinary wire lamps and owing to the short life of such lamps it is not commercial. Besides one must take into account that in lamps filled with gas the 35 emission of heat through the metal cap is rather high. Therefore, in order to keep the losses of heat down, it is necessary to proceed quite differently.

The device according to the present invention 40 has an interchangeable lamp filled with an inert gas, this lamp constituting the lamp proper and being provided with the metal wire or other filament and a small metal cap of special construction. This 45 lamp or burner is inserted in and almost entirely surrounded by a separate double-walled glass bulb or Dewar vessel exhausted between the outer and inner walls in such a fashion as to render the losses of heat, 50 especially the heat emission through the cap and fittings, as insignificant as possible.

Figures 1, 2 and 3 of the drawings affixed to this specification show some forms of an improved glow lamp according to my inven-

tion, all the modifications being represented 55 in longitudinal section.

Fig. 4 shows the plug *g* of Fig. 1 in cross section and illustrates the means for securing electrical connection between the terminal plugs *i*, *h* of the same. 60

Fig. 5 shows the plug *g'* of Figs. 2 and 3 in cross section and illustrates the means for securing electrical connection through the same.

Fig. 6 illustrates the slotted perforations 65 in the sleeve *c*.

In the lamp shown in Figure 1 *a*, *b* is the double-walled protecting envelop. A slender lamp *d* is inserted in the hollow of the double-walled bulb *a*, *b*; the filament is not 70 shown for the sake of clearness. A metal sleeve *c* is cemented into and thus becomes a portion of the neck of the double-walled bulb *a*, *b*, the inner part of said sleeve being slotted in order to keep its heat-conductivity 75 as low as possible. The outer part is provided with screw threads both internally and externally. The lamp *d* is provided at its base with a terminal ring *e* and a terminal block *f*. A separate screw-threaded 80 heat-insulating plug *g* is screwed into the sleeve *c*, said plug being provided with terminal blocks *i* and *h*. If the plug is screwed down into the sleeve *c*, block *i* coming in contact with block *f* of the lamp presses 85 ring *f* against the inner flange of the sleeve. When the whole device is screwed into a lamp holder the current will flow through sleeve *c*, ring *e*, the lamp filament and blocks 90 *f*, *i* and *h*. The distance *k* between the contact face of terminal *f* of the lamp and the end of the double-walled bulb being rather 95 long and there being no broad metal surfaces provided in this lamp which might favor the transmission of heat to the outside, the transmission of heat to the cap is very low indeed.

In the modifications shown in Figs. 2 and 3 the heat-insulating plug *g'* is screwed into the neck of the protective envelop *a'*, *b'*, 100 either a screw threaded metal sleeve *l* being cemented into the neck, or the glass walls *m* of the neck being themselves screw-threaded. The lamp *d'* is provided with a screw-threaded metal cap *n* designed to be 105 screwed into a corresponding metal sleeve *n'* of the plug, said plug being provided with a terminal block *q* at one end, and

with a screw threaded cap *o* and terminal block *p* to be inserted in the lamp holder, at the other end. The plug is preferably hollow and exhausted in order to get a better heat insulation.

5 I claim:

1. An electric lighting device, comprising an incandescent lamp, a two-part vacuum insulating means entirely surrounding the 10 lamp, preventing heat escape from the lamp in all directions and permitting the removal of the lamp.
2. An electric lighting device, comprising in combination an incandescent lamp containing a body of gas, and vacuum insulation means including a hollow lamp carrying member, for minimizing the escape of heat transversely and axially at both ends of said lamp.
3. In an electric lighting device, the combination with a gas filled incandescent lamp, and a socket in which the same is mounted; of a heat insulating pocket-like double-walled vacuum envelop adapted to inclose 25 both lamp and socket and readily detachable therefrom, said envelop including a heat insulating plug adapted to close the aperture of introduction of said envelop.
4. In an electric lighting device, in combination a gas-filled incandescent lamp having a socket, a pocket-like double walled exhausted envelop inclosing said lamp and socket, and a heat insulating plug, extending transversely across the lamp axis and the 35 aperture of introduction of said envelop, and adapted to effect heat insulation axially of said lamp.
5. In an electric lighting device, the combination with a gas filled incandescent lamp, and a socket in which the same is mounted; of a heat insulating pocket-like double-

walled vacuum envelop adapted to inclose both lamp and socket and readily detachable therefrom, and a heat insulating plug associated with said socket and adapted to effect 45 electrical connection with the lamp.

6. In an electric lighting device, in combination, a gas filled incandescent lamp, a double-walled protective glass envelop exhausted between its outer and inner walls 50 surrounding said lamp and a plug adapted to close the aperture of introduction of said envelop and to effect an electrical connection between said lamp and a lamp holder, said plug being hollow and exhausted.

55 7. In an electric lighting device, in combination, a gas filled incandescent lamp, a double-walled protective glass envelop exhausted between its outer and inner walls 60 surrounding said lamp, a heat insulating plug removably arranged in the neck of said envelop, a screw-threaded sleeve associated with said plug, a screw cap on said lamp adapted to be screwed into the plug sleeve and means for securing electrical connection 65 between the sleeve and a lamp holder.

8. In an electric lighting device, in combination, a gas filled incandescent lamp, a double-walled protective glass envelop exhausted between its outer and inner walls 70 surrounding said lamp, a heat insulating plug removably arranged in the neck of said envelop, a screw threaded sleeve associated with said plug, and a terminal on said lamp adapted to make an electrical connection 75 with said sleeve.

In testimony whereof, I affix my signature, in the presence of two witnesses.

EUGEN ESSICH.

Witnesses:

ANTON ARETZ,
ERNEST ENTLEMAN.
